UNITED STATES PATENT OFFICE.

CHARLES E. ANDERTON, JR., OF MILWAUKEE, WISCONSIN, ASSIGNOR TO WALTON DUPLEX COMPANY, OF CHICAGO, ILLINOIS, A CORPORATION OF ILLINOIS.

REVERSIBLE SHIRT.

Application filed October 12, 1922. Serial No. 594,129.

To all whom it may concern:

Be it known that I, CHARLES E. ANDERTON, JR., a citizen of the United States, and resident of Milwaukee, in the county of

5 Milwaukee and State of Wisconsin, have invented new and useful Improvements in Reversible Shirts, of which the following is a description, reference being had to the accompanying drawings, which are a part 10 of this specification.

This invention relates to improvements in men's shirts, and more particularly to a reversible form of shirt.

15 Heretofore, shirts have been constructed so as to have a right and a wrong side, or only one wearing side. The collars and cuffs of a shirt usually wear out long before the body portion does and when that happens, the shirt must be discarded. Also, the right 20 side of the shirt soils very quickly, particularly the collar and cuffs, and this requires very frequent laundering of the form of a shirt now in common use.

It is one of the objects of the present 25 invention to overcome the above mentioned difficulties by providing a shirt, which is reversible, thus giving two wearing sides, thereby prolonging the life of the shirt as well as lessening the frequency with which 30 it must be laundered.

A further object of the invention is to 35 provide a reversible shirt which is equally well finished on both sides and gives a neat appearance when either side is worn on the outside, not differing on either side from the appearance of the ordinary form of shirt.

A further object of the invention is to 40 provide a reversible shirt which uses but one set of buttons for both sides of the shirt, and which has reversible collar and cuffs.

A further object of the invention is to 45 provide a shirt which may be easily reversed to use either side.

A further object of the invention is to 50 provide a reversible shirt which is very simple in construction, is easily made and is desirable in use.

With the above and other objects in view,

the invention consists of the improved reversible shirt and its parts and combinations as set forth in the claims and all equivalents thereof.

In the accompanying drawing, in which the same reference characters indicate the same parts in all of the views:

Fig. 1 is an illustration of a man wearing the improved reversible shirt;

Fig. 2 is a vertical longitudinal sectional view of the rear of the shirt and showing the construction of the collar and the various adjacent seams;

Fig. 3 is a fragmentary view of the front underflap of the shirt showing how the buttons are secured thereto;

Fig. 4 is a vertical sectional view taken on the line 4—4 of Fig. 3;

Fig. 5 is a fragmentary view of the front outer flap of the shirt having therein the button holes;

Fig. 6 is a sectional view taken on the line 6—6 of Fig. 5;

Fig. 7 is a side view of a portion of a sleeve having a cuff attached thereto, parts being broken away and shown in section; and

Fig. 8 is a transverse sectional view taken on line 8—8 of Fig. 7.

Referring to the drawings, the numeral 11 represents a shirt, having a body portion 12, sleeves 13, cuffs 14, a collar 15, and flap portions 16 and 17. The collar band 18 is joined to the body portion 12 by means of a shoulder and back strip 19 which is integral with the shoulder strips and extends across the upper portion of the back portion of the body adjacent the collar band from one shoulder to the other and is formed in two plies 20 and 21. The lower ends of plies 20 and 21 are tucked in and hold the upper edge of body portion 12 therebetween, as at 22, and as shown in Fig. 2. The upper edges of the two plies of the shoulder strip 19 meet and are sewed between the two plies 23 and 24 of the collar band 18, said plies being also tucked in as at 25. The upper edges of the plies of the collar band are also tucked in, as at 26, and have sewed therebetween an

- edge of the collar 15, said collar being formed of two plies 27 and 28 which meet at 26. The other edges of the plies of said collar 15 are tucked in and sewed together, 5 as at 29. In Fig. 2, the full lines show the collar in its upright position ready to be folded, while the dotted lines represent it in either of its folded positions showing how it can be worn on one side or the other.
- 10 Where the body portion 12 of the shirt joins in the front, two longitudinal flaps 16 and 17 are provided. Flap 17 is the innermost flap and to form it, the material is turned back to give a double thickness, as 15 shown in Fig. 4, and hemmed. Flap 17 is provided with a longitudinal row of spaced apart transversely extending apertures 30, each of which has secured, preferably to its upper edge forming said apertures, as at 31, 20 by means of a sufficient length of thread 32, a button 33, said buttons being so secured that they may be swung through the apertures 30 to either side of the material, as indicated by the dotted lines in Fig. 4.
- 25 The outermost flap 16 has stitched thereto an additional strip 34 in the manner shown in Fig. 6, so as to give it additional thickness. Said flap 16 also has therein a longitudinal row of button holes 35 spaced to 30 correspond with the positions of said buttons 33 on the flap 17. Said button holes 35 are sewed to present a finished appearance on both sides.
- 35 The extremities of the sleeves 13 are finished with cuffs 14 which are of the form commonly known as "French Cuffs", and with which negligee shirts are usually provided. Thus, they may be easily reversed by folding one way or the other along the 40 edge 36. The sleeves 13, above the cuffs, have a slit or opening 37 so as to insure a correct meeting of the cuff edges and one side of said sleeves has sewed thereto along the slit, a reinforcing strip 38 in the manner shown 45 in Fig. 8.
- If desired, the shirt may be formed so that the points of the collar 15 will button on the bosom of the shirt. When that is the case, the bosom of the shirt, at points adjacent the points of said collar, is provided 50 with apertures carrying therein a swinging button, the same as shown in Fig. 3.
- 55 From the above description, it is apparent that the shirt may be worn on one side or the other. When it is desired to reverse the shirt, the sleeves are pulled inside out, the collar is folded over on the opposite side, and the buttons are pushed through their apertures so as to be toward the front. The 60 shirt is then ready for wear, and will have the appearance of the ordinary form of shirt, and neither side of the shirt will detract from its appearance in that respect.
- 65 From the foregoing description it will be seen that the improved shirt is simple, ef-

ficient and easily constructed and reversed, and is well adapted for the purposes described.

What I claim as my invention is:

1. As a new article of manufacture, a 70 complete reversible shirt including a collar formed as an integral part thereof and having a body portion, a neck band, and shoulder strips, the neck band being formed of a pair of strips, the shoulder strips being arranged in pairs, the adjacent edges of one of said pairs of strips being embraced by and secured between the adjacent edges of the other, the shoulder strips also embracing edges of the said body portion to provide an overlapping engagement on two sides between the neck band and the collar and the shoulder strips and the body to form substantially the same appearance 75 in either position of use. 80

2. As a new article of manufacture, a 90 complete reversible shirt including a collar formed as an integral part thereof and having a body portion, a neck band, shoulder strips, sleeves and cuffs, the shoulder strips being joined together across the upper portion of the back, said neck band and shoulder strips being formed of double thickness, the neck band overlapping both sides of the collar and parts of the body portion, and the shoulder strips embracing the body portion, there being an overlapping engagement 95 between the shoulder strips and the neck band, all of said parts presenting substantially the same appearance in either position of use. 100

3. As a new article of manufacture, a 105 complete reversible shirt including a collar formed as an integral part thereof and having a body portion, a neck band, sleeves and cuffs, the body portion being provided with shoulder strips which are connected together across the upper portion of the back, and the sleeves having elongated cuff slits with parallel edge portions, the upper ends of 110 which are in the same plane, said neck band and shoulder strips being of double thickness and each embracing the body portion, all of said parts presenting substantially the same appearance in either position of use. 115

4. As a new article of manufacture, a 120 complete reversible shirt including a collar formed as an integral part thereof and having a body portion, a neck band and shoulder strips, said body portion being divided longitudinally at its front to form flaps and having reversible flap securing means, said shirt also including sleeves and cuffs, the sleeves having elongated cuff slits with parallel edge portions, the upper ends 125 of which are in the same plane, said neck band and shoulder strips being of double thickness and each embracing the body portion, all of said parts presenting substantially the same appearance in either position of use. 130

5. As a new article of manufacture, a complete reversible shirt including a collar formed as an integral part thereof and having a body portion, a neck band and shoulder strips, said body portion being divided at its front and having front flaps, said shirt also including sleeves and cuffs, the shoulder strips extending across the back, said neck band and shoulder strips being of double thickness and embracing the collar and the body portion, said neck band also embracing the shoulder strips, the sleeves having elongated cuff slits with parallel edge portions, the upper ends of which are in the same plane, all of said parts including the collar presenting substantially the same appearance in either position of use.
6. As a new article of manufacture, a complete reversible semi-dress shirt including a collar formed as an integral part thereof, and having a body portion, a two ply neck band having the upper and lower edges of each ply turned inwardly, two ply shoulder strips extending only across the shoulders and back and having the lower edges of each ply turned inwardly, the upper edges of the shoulder strips being embraced by and between the inturned lower edge portions of the neck band plies and the inner edge portion of said collar being embraced by and between the inturned upper edge portions of the neck band plies, the upper edge of said body portion being embraced by and between the inturned lower edge portion of said shoulder strip plies, said body portion being divided longitudinally at its front to form flaps and having reversible flap securing means secured thereto, said shirt also including sleeves and cuffs, the sleeves having elongated slits with parallel edge portions, the upper ends of which are in the same plane, all of said parts presenting the same appearance in either position of use.

In testimony whereof, I affix my signature.
CHARLES E. ANDERTON, JR.
